UNITED STATES PATENT OFFICE

2,453,546

CIRCUIT BREAKER

Ezra S. Smith, Attleboro, Mass., assignor to
 Metals & Controls Corporation, Attleboro,
 Mass., a corporation of Massachusetts

Application October 30, 1944, Serial No. 560,929

4 Claims. (Cl. 200—116)

1

This invention relates to electric circuit breakers, and more particularly to circuit breakers which automatically trip out on overload in the electrical circuit, and which are manually reset to close the circuit again.

The invention is an improvement over that shown in the United States Patent 2,371,672, dated March 20, 1945, for Circuit breakers.

Among the several objects of the invention may be noted the provision of a thermostatic circuit breaker which has all of the advantages of the circuit breaker specified in said patent and which in addition is a two-rating breaker having a lower rating for the current under which thermostatic overload action occurs and a higher rating for functioning as a short-circuiting cutout; and the provision of additional means whereby both the thermostatic and short-circuiting components may under emergency conditions be opened independently of the thermostatic and short-circuiting operations. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a top plan view of the device;

Fig. 2 is a right end elevation of Fig. 1;

Fig. 3 is a bottom plan view of Fig. 1;

Fig. 4 is a section, on an enlarged scale, on the line 4—4 in Fig. 1;

Fig. 5 is a section, on an enlarged scale, on the line 5—5 in Fig. 1;

Fig. 6 is a section, on the line 6—6 in Fig. 2 with the thermal element dotted;

Fig. 7 is a section, on the line 7—7 in Fig. 2;

Fig. 8 is a section similar to Fig. 6 but with the thermal element shown in full and the heater dotted;

Fig. 9 is a view similar to Fig. 4 but showing the device in another position;

Fig. 10 is a view similar to Figs. 4 and 9 but with the device in a different position;

Fig. 11 is a view similar to Figs. 4, 9 and 10 but showing the device in still another position;

Fig. 12 is an isometric view of the operating handle mechanism; and

Fig. 13 is a perspective view of a fusible shunt bar, much enlarged.

Similar numbers indicate corresponding parts throughout the several views of the drawings.

Circuit breakers are of many different types. The present invention is concerned with thermal-type circuit breakers which utilize a thermal element both to open the circuit and to release as

sociated mechanism. Circuit breakers, in general, utilize either creep-acting thermal elements alone, or such creep-acting elements in conjunction with other apparatus to render the device snap-acting. Such structures have disadvantages for many purposes.

If such a circuit breaker is operating under conditions near its tripping point, the contact pressure exerted by the thermal element, or its position in relation to the detent which it may be controlling, may be so critical that a slight jar will often prematurely trip it. Also, in some types of thermal circuit breakers the thermal element is so arranged that during its actuation it drags against other parts with considerable friction, which results in non-uniformity of operation.

According to the present invention a circuit breaker is provided which is positive in its action, is not readily jarred into premature tripping, can be easily adjusted, opens the electrical contacts in a minimum of time and with ample opening to interrupt the arcs encountered in the circuit for which the circuit breaker is designed, and which is so arranged in relationship of its parts that the thermal element presents no hindering friction against any moving part.

The thermal element employed is an inherently snap-acting thermostatic member, plate or disc. Up to the point of tripping, this snap-acting element does not move, and hence maintains a positive latching action in conjunction with the detent which it releases, and hence is not readily jarred from its detent position. In addition, when the snap-acting element does snap, it clears the moving parts completely and the device is therefore free of the disadvantage encountered where the friction above referred to is present. Also, the pressure exerted by other moving parts in the circuit breaker has but little effect upon the calibration of the circuit breaker of the present invention.

In some types of circuit breakers it is necessary to incorporate what is called a shorting or shunting bar so that in an emergency the circuit may be closed to give a temporary control over the circuit in spite of the fact that the circuit is under overload conditions. In certain of these circuit breakers the manner in which this is accomplished is to cause the thermal element itself to act as a shunt bar. This may give trouble since the overload conditions are then apt to overheat and change the calibration of the thermal element and hence of the circuit breaker. In this invention the shunt bar is used in such a way that it completely shunts out the thermal element and little, if any, current passes through the thermal element when the shorting bar is in use. In addition, this actuation of the shorting bar, while being accomplished by the same control handle which is used to reset the breaker,

is so arranged as to have no restraining effect on the thermal element, which is at all times free to move.

The particular new features in connection with the present improvement are as follows:

First, the shunt or shorting bar is arranged as a new and improved fuse element which has a higher current rating for blowing than the current rating at which thermostatic operation occurs.

Second, manual means is provided for reopening the switch at will.

Referring now to the drawings, numeral 1 indicates a frame or base made of an electrical insulating material such as a molded synthetic resin of the "Bakelite" type. The base 1 is constructed of two parts 3 and 5. Molded into this base are grooved abutments, etc., illustrated generally at 7 (Fig. 6) tending to hold the various parts in alignment. Extending from the base are upright partitions 9 which form a channel 11 in which the boat or cam member 13 rides. Pegs 15 are inserted firmly and immovably in the base and serve as anchors for ends of the springs 17. The other ends of the springs 17 are respectively attached to the stirrup 19.

The construction of the slidable boat 13 is illustrated particularly by Fig. 12. The boat is, as indicated, of two main portions, the slide 21 and the frame 23. These are formed of thin sheet metal with sufficient rigidity to keep their shape. In addition to these two main parts there is a third part, the disc post indicated generally at 25. This post 25 is formed of steel or some other such metal. It has a threaded hub 27 which threads into the disc hub 29 (see Fig. 4), and a circular base portion 31. Two pins 33 project from diametrically opposite points on the circular portion 31 and are slidably engaged in the cam slots 35 of the frame 23. Bent-over ears 37 on the frame 23 serve to slidably hold the slide 21 to the frame 23, thus providing for a relative sliding between the frame 23 and slide 21. This motion is in a lengthwise direction. The slide 21 is provided with an elongated center opening 39, through which the threaded hub 27 of the disc post 25 is allowed to extend freely when the boat is assembled.

Slide 21 is also supplied with projecting ends 41, the purpose of which will subsequently be described. The other end of slide 21 is provided with a projection 43 to which the knob 45 is attached. The knob may be held on by any of the customary means.

One point in regard to the structure of the breaker of the former patent was that it was not intended manually to be reopened because the knob 45 was of plain cylindric form. Not enough friction would be obtained between such a form and the fingers, even with knurling of the knob to accomplish opening. As will appear from the following, opening action requires a substantial force. Therefore, herein the knob 45 is provided with a head 46. Thus the present construction provides an additional function.

The frame 23 has at one end notches 47 which serve to be engaged by the stirrup 19, and thus guide the stirrup in position on the frame 23, the stirrup being kept in position against the frame 23 by the springs 17.

Fig. 6 shows the boat mounted in the base 1. It will be observed that the stirrup 19 is engaging the end of the frame 23 in notches 47 so that when the knob 45 is pressed to slide the boat inward, the springs 17 provide a return bias.

The projecting pins 33 of the disc post 25 extend beyond the sides of the frame 23, and fit slidably into vertical notches 49 which are molded into the upright partitions 9. Thus, when the boat 13 is pushed along the base, the disc carrier post 25 cannot move along with it, but must move up and down in a direction perpendicular to the base, as viewed in Fig. 1. This up-and-down movement is caused by engagement of the pins 33 in the cam slots 35 in the sides of the frame 23.

Referring now to Fig. 13, there is shown a shunting or shorting bar 51. This bar in the present structure is improved over the bar shown in said patent. In the present case it is composed of an insulating strip 2, composed, for example, of compressed "Bakelite" impregnated cloth. Any insulating fibre is satisfactory if not frangible. On one side of the strip 2 is a facing 4 which is composed of a thin sheet of fusible copper, the ends of which are made up as two silver contacts 6. The latter are formed over the ends of the strip 2. Through this assembly are formed two holes 53, which holes receive the extensions 41 of the slide 21 to guide the shorting bar. The shunt bar 51 is shown mounted in position on the base with the extensions 41 passing through the holes 53 (see Figs. 6 and 9). A spring 55 rests in a properly provided groove 57 molded in the base 1. A metallic tube 59 serves to guide the spring and provide a mounting for it. Spring 55 is of such length as to keep the shorting bar 51 pressed away from the end of the base and toward the center of the base in a non-contact-making position.

The fusible facing 4 is intended to fuse at a current rating which is higher than that causing operation of a bimetallic disc 61 hereafter to be described in detail, but below the point at which other parts in the circuit would be damaged under shunt or short-circuiting conditions. A typical example will be specified later.

Referring again to Figs. 4 and 8, a thermostatic snap-acting bimetallic disc 61 is shown threadably mounted by means of hub 29 on the post 25. The hub 29 is provided with the proper abutments and shoulders in the usual way so that disc 61 is relatively free to rotate thereon. Thus by turning the disc hub 29 on the threaded hub 27, the position of disc 61 is changed relative to the base 5. By this means temperature adjustment of the disc is made. Contacts 63 are electrically welded on disc 61, or otherwise mounted and electrically connected to the disc 61.

Referring now to Fig. 7, the terminal and stationary contact assembly is shown with the internal heater. These are as follows: One terminal 65, comprising a strip of conducting metal of the proper thickness and size to fit in the grooves 7 molded in the base, is shown pressed into position. This terminal has a contact 67 on its side facing the central portion of the circuit breaker positioned to engage one of the disc contacts 63. The other terminal 69 is likewise mounted on the base, and to it is attached at one end a heater 71. The other end of heater 71 is attached to a third metal support 73 which likewise engages the molded grooves in the base 1. Support 73 is not in electrical contact with terminal 69, except through the heater 71. Support 73 carries on its inner surface a contact 75 which is adapted to engage the other contact 63 on the bimetallic disc 61. In addition to these contacts, terminal 65 carries on it an additional stationary contact 77 adapted to be engaged by one end of the shunt bar 51, and terminal 69 carries a sta-

tionary contact 78 which is adapted to be engaged by the other end of the shunt bar 51.

It is to be understood that the heater element 71 may be omitted in this case where the rated current is great enough that the heating caused by its passage through the disc 61 alone is great enough to cause the thermostatic action of the disc. In general, the switches with lower current ratings require the heater because a point is reached where the cross section of the disc cannot be reduced to an area small enough to bring about the heating required in view of the current available. In other words, the disc has a limiting thinness for proper mechanical operation. It is in such cases that the auxiliary heater is used because its cross section is independent of any mechanical strength requirements. Its cross section may be made whatever is necessary to bring about the heating desired.

Referring to Fig. 5, there is shown a post button 81 having a threaded portion 83 and a projecting stem 85. This post button screws into the base portion 5 (see also Fig. 3), which has a hole 87 threaded for that purpose. Projecting stem 85 slidably fits into the hole 88 which is provided centrally in the disc post 25. This stem portion 88 and the notches 48 serve as the bearings on which the post 25 rides up and down when the boat 13 moves back and forth in the base. It will be observed that a molded portion (see Fig. 6) serves to engage the extending ears 93 of the disc 61, and thus maintain the respective contacts in alignment.

It will be observed that as the boat 13 moves along the base in its channel 11, the disc post 25 rides up and down in a direction perpendicular to the plane of motion of the boat 13. As the disc post 25 does this, it carries up and down with it the snap-acting bimetallic disc 61. Thus the contacts 63 are brought into engagement with the stationary terminal contacts as the boat 13 slides along the base against the tension of the springs 17, and vice versa. The operation of these motions is such that when the boat is moved by means of the knob 45 along the base, the pins 33 are forced by the cam slots 35 in an upward direction (as Figs. 6 and 8 are drawn) so as to bring the disc and its mating circuit-closing contacts into engagement with the stationary contacts 67 and 75. When the disc contacts 63 reach the stationary contacts 67 and 75, the motion of the perimeter of the disc is stopped, but further motion of the slide forces the center of the disc still farther upward, thus putting pressure on the cold disc which is resisted by the spring characteristic of the disc itself. When the boat is pushed further along, the pins 33 ride up over the curved detent parts 95 of the cam slots 35. To make the pins ride up over the detent parts 95 against the pressure of cold disc 61, an additional force is required. Consequently when the pins drop down behind the detent parts 95, the spring pressure of disc 61 serves to hold the boat in position against the tension of springs 17, as long as the pressure is maintained against the pins by the cold disc 61. The ends 97 of the slots 35 back of each detent part 95 are preferably thus a little longer than actually required, to make sure that the pins 33 will drop down.

Assuming that the parts are in this position, we will see that there is an electrical circuit through the terminal 65, contact 67, the corresponding contact 63 of the disc, disc 61, the other

disc contact 63, the stationary contact 75, heater 71 and terminal 69.

The overload tripping operation of the device on overload conditions is as follows:

5 When the device is subjected to the overload current which it is designed to interrupt, the heater 71 heats up as does the disc 61 (since it is subjected to the current also). After a predetermined given interval of time, the heat generated is sufficient to cause the disc to snap to its other (hot) position of concavity. This motion of the disc in its snap opens the contacts and also serves to release the pressure of the pins 33 against the detent 95, and the biasing springs 17 are now 10 free to pull the boat 13 back into its original position. This motion of the boat 13 causes the cam slots 35 to draw the hot disc 61 away from the stationary contacts 67 and 75. It will be observed that if the knob and boat are held in the 15 circuit-closing position, the motion of the disc snaps the contacts 63 away from contacts 67 and 75, thus opening the circuit. The automatic movement of the disc caused by the boat 13 and its cam action is large compared to the motion 20 obtained from the thermal movement of the disc alone and gives the breaker additional circuit-interrupting capacity. In addition, this movement caused by the cam action is sufficiently large so that when the disc cools and snaps back to its 25 original cold position, the contacts 63 do not make contact with the stationary contacts 67 and 75 mounted on terminals 65 and 69. Thus, with the disc in its cold position, and until reset, the circuit is maintained in an open position.

35 It will accordingly be observed that the opening of the circuit is caused by a combination of the motion of the disc and the motion of the boat. Also, that the motion of the disc alone is sufficient to open the circuit, and the device is thus 40 trip-free of the handle when the latter is in its normal circuit-closed position. That is, pushing in the handle while the disc is snapped to hot position will not re-close the circuit through the disc.

45 The purpose and operation of the shorting bar is as follows:

It sometimes happens that in an emergency it is necessary to prevent the circuit breaker from 50 interrupting the circuit, or else to quickly re-close the circuit if the circuit breaker has opened it. To this end the shunting bar 51 is provided. By referring to Fig. 12, it will be seen that the slide 21 can move relative to the frame 23. Consequently a further inward pressure on the knob 45 will cause the slide 21 to slide in a little further. This further sliding action results in the end of the slide 21 at the ends of its extensions 41 striking the shunt bar 51 as shown in Figs. 9 and 11, 55 and forcing the bar 51 into engagement with the stationary contacts 77 and 79. Consequently this further forward motion of the slide 21 will enable the circuit to be closed, regardless of the position of the disc (see Figs. 9 and 11; Fig. 9 illustrates 60 the condition where the disc is in its cold position and Fig. 11 where the disc is in its hot position).

From the above it will be understood that this further forward motion of the slide 21 will enable the circuit to be closed, regardless of the position of the disc, and likewise that this in no way interferes with the operation of the disc. It will be observed that the shunting bar 51 effectively shunts out the heater 71 and the disc 61, so that neither is injured by the overload current. When 65 the pressure on knob 45 is relieved, the spring 55

forces the shorting bar away from the contacts 77 and 79, thus opening the shunting circuit.

As above forecast, by making the short-circuiting bar 51 of fusible material it may be designed itself to cutout operation if the short-circuiting current is high enough to melt the fusible element 4. Thus the switch as a whole has two ratings, namely, a lower rating for the current at which thermostatic operation occurs and a higher rating at which the fusible element 4 burns out. For example, a typical rating for action of thermostatic disc 61 might be 5 to 50 amperes and 600 amperes for the fusible link 4. It is to be understood that these ratings are only exemplary and that others might be used. The insulating stiffening bar 2 allows the fusible short-circuiting bar to be designed thin enough for any desired capacity without rendering the bar as a whole too flexible for proper mechanical operation.

An important factor of this construction is that by allowing relative movement between the slide 21 and the frame 23, the spring 55 can be made fairly light and still be strong enough to force the slide 21 back, and hence open the shunt bar circuit. It has been found that if the disc 61 is in its cold circuit-closed position there is considerable pressure exerted against the frame 23. If frame 23 and slide 21 were all of one piece, the whole of said piece would have to be moved inward to close the shorting bar. The friction caused by the disc pressure against the frame 23 and the frame against the base would be sufficient to hold the shorting bar closed, even if the knob 45 were released, unless a very strong spring 55 were used. As a practical matter, it is found that the spring 55 would have to be so strong as to make it difficult, if not impossible, to fit it into the small space required by efficient design of a circuit breaker of this type. Also, the use of such a strong spring would make it very difficult to close the shorting bar. By the present construction a light spring is allowed to work against the freely-moving slide 21 to open the shorting bar. Also, the lost motion between prongs 41 and bar 51 avoids a large initial deflection in the spring 55 such as would be necessary if the bar 51 partook of the full stroke of 21. This is further conducive to a short spring.

From the above it is clear that the present circuit breaker is the type which utilizes a thermal means to initiate the mechanical motion, said mechanical motion further moving the thermal element. The motion of the thermal element per se will serve to open the circuit with a snap action. This quick opening tends to minimize burning of the contacts by arcing. Also, the disc when in its hot position exerts no pressure against the boat, and hence the boat is free to be moved back by springs 17. The use of a snap-acting thermal element thus minimizes friction, since such an element occupies either its hot or cold position, any intervening position being of extremely short duration.

The spring 55 automatically re-opens the fusible circuit through the short-circuiting bar when the button 45 is released. Pull on the button is not needed for this purpose. Pull on the button afforded by the enlargement 46 allows the boat or cam member 13 to be pulled back so as to draw open the thermostatic switch member 61 when the latter is in a thermal condition otherwise to close the circuit. The reason for providing the enlargement 46 in order to obtain a positive manual grip is that a fairly substantial force is required to pull the detent 95 under the pins 33.

The substantial force is due to the fact that this requires some forceful flattening of the disc in its cold position against the contact 71. It will be noted on the other hand that a feature of the detent 95 is that it, in view of the tension from the disc 61, prevents the opening action of the switch from being too critical, that is, from opening accidentally under vibrating conditions due to action of the springs 17. Thus means is provided on the one hand for preventing accidental vibratory opening and on the other hand positively operable manual means providing for manual opening.

A portion of the knob 45 below the head 46, indicated at 48, may be colored differently than the remainder, such as, for example, red. Hence when the knob is pushed in, this part will be hidden by an encircling flange 50 of the plate or panel 107. When the knob 45 is pulled out, this differently colored portion will be exposed to indicate that the thermostatic disc 61 is in open position.

An advantage of the particular form of bar 51 is that if a manufacturer desires to make some part of his production of switches without the short-circuiting feature, it is only necessary to eliminate the fusible link 4 along with its contact 6 simply by not assembling them on the insulating bar 2. Then the holes in the bar 2 will still function to receive the fingers 41, but the short-circuiting operation will be dead. This is to be distinguished from leaving out also the spring 55 and the bar 2 for the elimination of short-circuiting, in that the holes 53 in the insulating bar 2 still act as guides for the fingers 41.

Referring to Figs. 1 and 3, through the holes 99 are passed rivets which serve to hold the two halves of the base together. Referring again to Figs. 6 and 7, just before the two halves of the base are put together, nuts 103 are inserted in properly shaped hexagonal recesses 105 in each half of the base, so that when the two halves are put together nuts 103 are held so that they cannot turn. Then the frame 107 which serves to mount the breaker on the proper panel is held firmly to the base by means of screws 109 which engage the nuts 103.

To adjust the circuit breaker to the proper rating, the button 81 is unscrewed, thus giving access to the disc hub 27. This is turned (thus changing the temperature adjustment of the disc) until the disc snaps at the correct interval of time, with the calibrating current flowing through it and its heater. A drop of solder is then placed on the hub to solder it to post 25, and thus to prevent it from further turning and getting out of adjustment. In order to prevent tampering and resetting in the field, a cover disc 80 is cemented in place over the button 81.

While the thermostatic member 61 is, according to the present example, inherently stressed to be concave toward the first contacts 75 and 77 when cold, and vice versa, it is clear that this relationship of conditions could be reversed without changing the inventive principles. In other words, the second contacts 63 could be carried from the first contacts upon cooling, the two conditions of stability of the thermostatic member being reversed as regards temperature.

In view of the above, it will be seen that the several objects of the invention are achieved and other advantageous results attained.

As many changes could be made in the above constructions without departing from the scope

of the invention, it is intended that all matter contained in the above description or shown in the accompanying drawings shall be interpreted as illustrative and not in a limiting sense.

I claim:

1. A circuit breaker comprising separable contacts, a tripping mechanism for said contacts including a thermostatic element, manually operable means having a lost-motion connection with said tripping mechanism for reclosing said contacts after separation thereof and cooling of said thermostatic element, and a shunt switch adapted to be closed by said manually operable means upon taking up said lost motion for shunting said separable contacts and closing the circuit, the movable contact element of said switch comprising a fuse, thereby providing for insertion of a fuse into the circuit only upon shunting operation, control of said circuit being restorable to said separable contacts and tripping mechanism upon opening of said switch whether or not the fuse has blown during the shunting operation.

2. A circuit breaker comprising separable contacts, a tripping mechanism for said contacts including a thermostatic element, manually operable means having a lost-motion connection with said tripping mechanism for reclosing said contacts after separation thereof and cooling of said thermostatic element, and a shunt switch adapted to be closed by said manually operable means upon taking up said lost motion for shunting said separable contacts and closing the circuit, the movable contact element of said switch comprising a fuse, thereby providing for insertion of a fuse into the circuit only upon shunting operation, control of said circuit being restorable to said separable contacts and tripping mechanism upon opening of said switch whether or not the fuse has blown during the shunting operation, said fuse having a higher rating than the rating of the tripping mechanism for the separable contacts.

3. A circuit breaker comprising separable contacts, a tripping mechanism for said contacts including a thermostatic element, manually operable means having a lost-motion connection with said tripping mechanism for reclosing said contacts after separation thereof and cooling of said thermostatic element, and a shunt switch adapted to be closed by said manually operable means upon taking up said lost motion for shunting said separable contacts and closing the circuit, said switch comprising a pair of fixed spaced contacts and a movable contact element com-

prising a strip of insulating material having a facing of fusible conducting material and adapted to bridge said fixed spaced contacts and to fuse upon passage of an overcurrent therethrough, thereby providing for insertion of a fuse into the circuit only upon shunting operation, control of said circuit being restorable to said separable contacts and tripping mechanism upon opening of said switch whether or not the fuse has blown during shunting operation.

4. A circuit breaker comprising separable contacts, a tripping mechanism for said contacts including a thermostatic element, manually operable means having a lost-motion connection with said tripping mechanism for reclosing said contacts after separation thereof and cooling of said thermostatic element, said manually operable means being provided with means thereon whereby substantial force may be manually applied directly thereto to open said contacts when said thermostatic element is heated and said contacts are closed, and a shunt switch adapted to be closed by said manually operable means upon taking up said lost motion for shunting said separable contacts and closing the circuit in an emergency, said switch comprising a pair of fixed spaced contacts and a movable contact element comprising a strip of insulating material having a facing of fusible conducting material and adapted to bridge said fixed spaced contacts and to fuse upon passage of an overcurrent therethrough, thereby providing for insertion of a fuse into the circuit only upon emergency operation, control of said circuit being restorable to said separable contacts and tripping mechanism upon opening of said switch whether or not the fuse has blown during shunting operation, said fuse having a higher protective rating than the rating of the tripping mechanism for the separable contacts.
